UNITED STATES PATENT OFFICE

98,974

DESIGN FOR A BEVERAGE DISPENSING DEVICE

Everett Worthington, Chicago, Ill., assignor to Coca-Cola Company, Atlanta, Ga., a corporation of Delaware

Application September 18, 1935, Serial No. 58,615

Term of patent 14 years

To all whom it may concern:

Be it known that I, Everett Worthington, residing at Chicago, in the county of Cook and State of Illinois, have invented a new, original, and ornamental Design for a Beverage Dispensing Device, of which the following is a specification, reference being had to the accompanying drawings, forming part thereof.

erage dispensing device, showing my design;

Fig. 2 is a top plan view thereof;
Fig. 3 is a front elevational view thereof;
Fig. 4 is a rear elevational view thereof; and
Fig. 5 is a bottom plan view.

I claim:

The ornamental design for a beverage dispensing device, as shown.
